UNITED STATES PATENT OFFICE.

WALTER J. WISCH, OF BALTIMORE, MARYLAND.

APPARATUS FOR MAKING HOLLOW BALLS.

Application filed December 22, 1920. Serial No. 432,465.

To all whom it may concern:

Be it known that WALTER J. WISCH, a citizen of the United States, residing in Baltimore city, State of Maryland, has invented certain new and useful Improvements in Apparatus for Making Hollow Balls, of which the following is a specification.

My invention relates to apparatus adapted for working hollow metal ball blanks by combined hammering and rolling.

I have found that suitable hollow blanks may be treated by a combined rolling and hammering process with improved results, particularly in the economical production of completed hollow balls with true surface, wall of uniform thickness, and with the opening contained by the blank very uniformly and homogeneously closed, and with other advantages sufficiently explained hereinafter.

The combined rolling and hammering operation may be performed in different ways, three representative ways consisting in (1) providing blanks having a more or less elongated or ovoid form, and rolling these blanks in suitable grooves formed in opposed plates, with suitable pressure, the ovoid shape of the blanks causing them to assume constantly changing positions, and to be bumped or hammered in the grooves as they are rolled, to reduce them to spherical form, and otherwise finish them as sufficiently explained hereafter; (2) providing spherical blanks, or, when ovoid blanks are provided, and the irregular shape of the blanks themselves is not considered sufficient to provide for proper hammering action, and rolling the blanks in a channel consisting of grooves formed in opposed plates, with suitable pressure applied to the plates, and with at least one of the grooves being provided with irregularities so that as the balls are rolled they are simultaneously hammered or bumped by the irregularities of the groove; (3) rolling the blanks in smooth grooves, with suitable pressure as before, and at intervals imparting impulses to one plate, urging it toward the other, with sufficient force and abruptness to produce a hammering effect upon the balls as they are rolled. The foregoing are considered to be sufficient examples of the method of treating the balls, in a broad sense, and mechanisms are here shown for carrying out the method

in any of the ways mentioned. After considering these exemplifications, persons skilled in the art will understand that the mechanisms may be varied within the principles of the invention, and I do not limit myself to details except as claimed.

In the drawing:

Fig. 1 is an elevation of a representative form of machine, some parts being shown in section.

Fig. 2 is a plan view of a modified form of rolling plate.

Fig. 3 is a section of a pair of such plates in operative relation.

Fig. 4 is a plan view of a straight rolling plate.

Fig. 5 is a transverse section of a pair of such plates in operative relation.

Fig. 6 is a section of a ball blank of one suitable form for treatment in the present apparatus, and

Figures 7, 8 and 9 are sections of the blank in successive stages of this treatment in the apparatus, Fig. 9 showing one form of completed ball.

In another application Serial Number 432,466, filed Dec. 22, 1920 I have described and illustrated more fully the process of treating balls, which is carried out by the present apparatus, and reference to that application is made for a complete understanding of the process, especially the preparation of suitable blanks, and the particular manner in which the blanks are worked in carrying out the process. The process will be mentioned herein only sufficiently to enable the structure, and the operation of the apparatus to be sufficiently understood.

Referring first to Fig. 1, a complete machine in one representative form comprises uprights 1, which may conveniently be round columns, and which may be clamped in bases or feet 2 resting on any suitable foundation. The upper ends of the columns are screwed into top piece 3, which carries bearings 4 and 5. The drive shaft 6 is supported in bearing 4, and has fast and loose pulleys 7, 8 for driving the machine, or any other suitable driving arrangement may be provided. A vertical shaft 9 is located in bearing 5, suitable clearance being provided between the shaft and the bearing, as shown. The shaft is driven from shaft 6 by pinion 10 and gear 11. The thrust of gear 11 may be taken up by

a ball thrust bearing 12. Below frame member 3 is located the revoluble rolling plate 13. A ball thrust bearing 13^a may be provided between plate 13 and transverse frame member 3. The plate 13 has a central transverse socket 14 in which engages a head 15 formed on the lower end of shaft 9, and sufficient clearance is provided between the head and the socket for a slight vertical reciprocation of the plate. Fixed rolling plate 16 is located below plate 13, and is bolted to a cross member 17 having sleeves 18 movably mounted on columns 1. The cross piece is supported, for the vertical adjustment of the fixed plate, by a thrust bearing 19 upon the upper end of a screw 20. This screw engages in sleeve 21 of frame cross piece 22 mounted on the columns. A hand wheel 23 is keyed to the lower end of the screw shaft.

The rolling plates provide between them at least one annular channel C composed of a groove g^1 of approximately semi-circular cross-section plate 13, and a groove g^2 of approximately semi-circular cross-section in plate 16. The grooves are so cut in the plates, or the plates are so surfaced off that a clearance remains between the plates when the plates are nearest together, sufficient to make the vertical dimension through the center channel C to the bottoms of g^1 and g^2 respectively, equal to the diameter of the ball when its treatment in this channel is completed. The grooves are usually relieved at the sides by bevels 25 which in effect take off the corners of the grooves, and prevent cramping of the balls at the sides of the grooves.

When ball blanks of elongated or ovoid form are placed in the grooves, the machine adjusted, and rolling performed as more particularly described hereafter, in many cases sufficient hammering of the blanks is accomplished by the elongated shape of the blanks themselves, since the blanks are continually presented to the grooves in different positions as they revolve, and when the elongated portions are directed nearly vertically, the blanks are hammered and compressed into proper form, at the same time that they are rolled. The clearance in bearing 5 permits shaft 9 to have a certain degree of lateral movement, and this in turn permits the movable rolling plate to move laterally to a slight extent in any direction, and thus the grooves are accommodated properly to the momentary position of the irregularly shaped blanks. In cases where the elongation of the blanks is not considered sufficient to provide for the necessary amount of hammering, or where it is desired to use spherical blanks, other or additional means for accomplishing the hammering action are provided.

One form of such hammering mechanism,

as shown in Fig. 1, consists in providing the top of plate 13 with an annular cam surface 30 consisting of alternate humps 31 and hollows 32, the height of the humps being considerably exaggerated in the drawing. The cam surface is engaged by a series of cam rolls 33, equally spaced about the center of shaft 9, and mounted on bearing pins 34 in cross piece 3.

The machine is loaded by turning hand wheel 23 to lower plate 16; a number of suitable blanks, such for instance as the blank B shown in Fig. 6, or spherical blanks, are placed in grooves g^2 , and the hand wheel is then rotated to bring the fixed plate up in proximity with rotatable plate 13, and to exert the desired amount of pressure upon the blanks. Driving connection is then made to shaft 6, and shaft 9 is rotated by the gears, rotating plate 13 and causing cam rolls 33 cooperating with cam surface 30 to apply intermittent hammer blows to plate 13, and these blows are transmitted to the ball blanks as they are rolled in the grooves. It will be noted that the hammering movement is at right angles to the rotation of the plate. By this treatment the balls are brought to uniform diameter, the walls are reduced to uniform thickness throughout, and the holes H of the blanks are very uniformly and homogeneously closed. The blank in its treatment in the grooves goes through the changes indicated in Figures 7, 8 and 9, as more fully explained in my method application above referred to.

When it is considered unnecessary to provide for positive hammering by means of a cam mechanism described, the cam action can be eliminated by simply removing the cam rolls 33 and the machine may then be used as previously described in rolling ovoid blanks with a combined rolling and hammering effect obtained from the shape of the blanks themselves.

The plates 13, 16 may be provided with an additional rolling channel C¹ consisting of grooves g^3 , g^4 , and these grooves may be of smaller radius (calculated from the center k) than the radius of grooves g^1 , g^2 . The balls after rolling in channel C may be finished, that is, rolled to a smaller diameter and the closure of the opening completed, in channel C¹, and with the arrangement of part shown in Fig. 1, this final treatment will be a combined rolling and hammering; but if desired, the final treatment may be merely a simple rolling, and this may be provided for by removing the cam rolls 33 or by otherwise arranging or adjusting the machine.

Figures 2 and 3 show rolling plates adapted for another method of combined rolling and hammering. In this arrangement, circular plates 40 and 41 are provided with annular channels C², C³, of which chan-

nel C² may be arranged for combined rolling and hammering of the balls, and channel C³ may be arranged for a simple rolling for finishing the balls, or this arrangement 5 may be reversed. Or, in some cases, both channels may be arranged for combined rolling and hammering. Channel C² is composed of groove g⁵ in plate 40, and groove g⁶ in plate 41. One of the grooves, for 10 instance g⁵, is provided at intervals with depressions 42, which may be, to give one example, of a form equivalent to depressions which would be produced by embedding somewhat in the surface of the groove 15 a sphere having a slightly larger radius than that of the groove. The depth of the depression is somewhat exaggerated in the drawing. The other groove may in some cases also be provided with depressions of a 20 similar character, although as a rule one groove is smooth, and the other provided with depressions or irregularities. These plates may be inserted in such a machine as the one shown in Fig. 1, with the omission 25 of cam rolls 33, or in any other suitable rolling machine, and when the channel is filled with a suitable number of ball blanks, and the plates are rotated in relation to each other with suitable pressure, the balls are 30 alternately rolled by the smooth parts of the channel, and hammered by encountering the edges of the depressions, thus giving the balls in effect a combined rolling and hammering treatment to render their diameter 35 and wall-thickness uniform, and close the opening, as more fully described in the process application above identified. The channel C³ may be a smooth finishing channel, consisting of smooth grooves g⁷, g⁸, with 40 depth calculated on a radius from the center k¹, slightly less than the radius of the grooves of channel C², or in some cases one or both of the grooves of channel C³ may be provided with irregularities or depressions, so that the final treatment of the balls 45 will be by combined rolling and hammering.

Figures 4 and 5 show a modification in which the rolling plates 50 and 51 are straight, and provided with straight channels C⁴, and C⁵ which are substantially 50 equivalent to the channels C² and C³ respectively of Figures 2 and 3, except that they are straight instead of annular. The channel C⁴ consists of grooves g⁹, and 55 g¹⁰, and at least one of the grooves, for instance g⁹ is provided with depressions 52, and channel C⁵ consists of grooves g¹¹, and g¹², both of which may be smooth. The treatment of the ball blanks in the two 60 grooves is substantially the same as in the case of the circular plates. The straight plates may be reciprocated relatively by any suitable mechanism while pressure is applied by any suitable means.

I claim:

1. In an apparatus for treating ball blanks or the like, means for simultaneously rolling and hammering the blanks at right angles to the path of rolling movement. 70
2. An apparatus for treating ball blanks or the like, comprising means for rolling the blanks, and intermittently pounding them at right angles to the path of rolling movement. 75
3. An appliance for treating hollow ball blanks or the like, comprising two plates provided with a channel consisting of confronting grooves on the adjacent faces of the plates, and means for intermittently and abruptly applying increased pressure to the blanks at right angles to the path of rolling movement as they are rolled in the channel. 80
4. In a machine for treating hollow ball blanks, the combination of two plates having grooves in their adjacent faces constituting a channel, means for urging the plates together to apply pressure to blanks located in the channel, means for moving one plate in relation to the other to roll the blanks, and means for intermittently and abruptly applying increased pressure to the blanks at right angles to the path of rolling movement as they are rolled. 85
5. In a machine for treating hollow ball blanks, the combination of two plates having confronting grooves in their adjacent faces constituting a channel to receive the blanks, means for rotating one of the plates in relation to the other, means for applying pressure to blanks located in the channel as they are rolled, and means for hammering the blanks at right angles to the path of rolling movement during rolling. 90
6. In a machine for treating hollow ball blanks, the combination of two rolling plates having confronting grooves to receive ovoid ball blanks to be rolled, and means for rotating one of the plates in relation to the other, said means comprising a drive shaft engaging the plate and a bearing for the shaft having considerable clearance to permit lateral movement of the shaft and plate to conform to the position of the blanks. 105
7. In a machine for treating hollow ball blanks, the combination of two rolling plates having confronting grooves forming a channel to receive the blanks, means for rotating one of the plates in relation to the other, and cam mechanism for applying to the rotating plate a series of abrupt, increased-pressure impulses, which are conveyed through the plate to the blanks to hammer them as they are rolled. 115

In testimony whereof I affix my signature.

WALTER J. WISCH.
